MAGAZINE RACK

Robert K. Ostrander, Jr., Fort Worth, Tex., assignor to Loma Plastics, Inc., Fort Worth, Tex., a corporation of Texas

Application December 12, 1958, Serial No. 780,001

5 Claims. (Cl. 211—50)

This invention is in the field of magazine racks and the like and is concerned with a plastic magazine holder having dimensional stability.

A primary object of the invention is a new and improved plastic magazine rack which is easy to use and inexpensive to manufacture.

Another object is a magazine rack having opposed plates pivoted at their lower edge, convex upwardly, and constructed to be biased together at their upper edges due to the weight of the magazines and the plates themselves.

Another object is a magazine rack of the above type with an inexpensive bent wire frame or base.

Another object is a corrugated plastic magazine rack having substantial lateral and vertical strength.

Another object is a magazine rack which is relatively open and at the same time is constructed to prevent magazines from falling out the ends thereof.

Other objects will appear from time to time in the ensuing specification and drawings in which:

Figure 1 is a perspective of the magazine rack;

Figure 2 is an end view of the rack in Figure 1;

Figure 3 is a section along line 3—3 of Figure 2 with the base or support omitted;

Figure 4 is a section along line 4—4 of Figure 3; and Figure 5 is a bottom view of Figure 4.

In Figures 1 and 2, the magazine rack has been shown as including a base or frame 10 which supports a receptacle or container 12. Considering the details of the base 10 first, it may include or be made up of a bent wire or the like having longitudinal side opposed lengths 14 bent downwardly at a suitable angle toward the ends thereof into leg portions 16 and suitably curved over and under to form well rounded feet or supports 18. Cross portions at the end rise initially at 20 to a cross or lateral guard 22. It will be noted that the vertical portions 20 are bent outwardly somewhat, as at 24 in Figure 1, so that the cross pieces or guards 22 are disposed outwardly beyond the feet 18 in Figure 1. It will also be noted in Figure 2 that the downwardly bent portions 16, in addition to diverging longitudinally, are also inclined somewhat laterally outwardly. Thus the frame presents two somewhat inwardly disposed longitudinal lengths 14 which support the receptacle or container 12, explained in detail hereinafter, and lateral members across the ends, including 20 and 22, in addition to closing the ends of the receptacle, as explained in detail hereinafter, also may function as handles.

The base may be made up of one continuous wire appropriately bent in the form shown or the like or it may be made in sections and suitably connected as by welding or otherwise. The precise angles, dimensions and radii of curvature are not considered important. The base or frame may be made symmetrical, both laterally and longitudinally, as shown in the drawings.

The container or receptacle 12 may include side plates 26 hinged together adjacent their bottom or abutting

2

edges 28, as explained in detail hereinafter. Since these plates may be identical but disposed symmetrically opposite each other, only one will be explained in detail hereinafter and it may be assumed that the other is or may be the same.

Each plate is disposed generally upright and is outwardly bowed or bent from its lower edge 28 toward its upper edge. As shown in Figure 2, each plate may have a lower outwardly diverging portion 30 and an upper 10 inwardly converging portion 32 integrally joined at a corner or bend 34. The angle between these two legs or portions may be on the order of from 90 to 100 degrees or it might be otherwise. The two portions or legs 30 and 32 have been shown as generally planar, each unto itself, but each such side or plate might be simply outwardly bowed or convex.

Be that as it may, each plate is provided with an outwardly turned or disposed upper lip 36 bent as at 38 at a suitable angle, say from 90 to 100 degrees, so that an 20 upwardly disposed trough or mouth 40 is provided.

As shown in Figures 3 and 5, the sides of the plates are vertically fluted or corrugated, as at 42, to provide dimensional stability and vertical strength. It is preferred that each of the plates or sides be molded entirely 25 of plastic, although a composition or fabricated structure may be used. It is preferred that the sides be simply vacuum formed of a suitable plastic, such as polyethylene or polyvinyl, but any suitable material may be used.

To function as abutments or supports for the hinges, 30 suitable outwardly disposed plate portions 44 may be suitably molded or otherwise formed at the lower edge of each of the side plates. As shown in Figure 3, two such plates are formed, as at 46 and 48, on each side plate to provide for two hinges. But more or less might be used. 35 Each such plate may have a plurality of suitable openings 50 so that brads, tacks or rivets or screws may be used to connect the hinges. As shown in Figure 4, each hinge may be formed of a suitable strap type element 51 which may be on the inside and totally free and flexible so that 40 the sides and plates may freely flex, as set forth in detail hereinafter.

These platelike portions 44 may be directly molded in the sheetlike side members and the corrugations may smoothly flow into these flat plate portions, as shown 45 in Figure 3, so that no break-up or decided change of the side pattern is necessary. The corrugations may terminate adjacent the lower edge 28 at fingerlike portions 52 so that except for the hinge plates 44, the lower edge 28 will be continuous and smooth. As shown in Figure 4, the lower 50 edge will be offset somewhat at the hinge plate 44.

The upper edge 54 may be well rounded in cross section, as shown in Figure 2, and the corrugations may flow smoothly into a flat coplanar edge forming fingerlike portions 56. As will be noted in Figure 3, the corrugations 55 in the plates extend outwardly so that the edges 28 of opposed plates will come together and will be generally flush.

Upper and lower outwardly extending abutments 58 and 60 may be formed integrally in the side plates along the lower portion 30 thereof. As shown in Figure 3, two such pairs of abutments are spaced evenly along the sides and, as will be noted in Figure 2, the length 14 of the bent wire frame or base is adapted to engage the bottom or lower surface 62 of the upper abutment 58 which functions as a pivot. Such abutments are on the crest of one of the outwardly disposed corrugations so that the length 14 of the wire base will run flush with the outer or high points of the corrugations. In the event that the receptacle 12 is rotated or tilted in its supporting frame so that the 65 upper abutment on one side slips below the rectilinear length 14, the lower abutment on the opposite side will

contact its length 14 to prevent the receptacle from turning over. It should be noted in Figure 2 that the lower surfaces 62 of the upper abutments are generally horizontal so that they will rest on the lengths 14, while the upper surface 64 of the lower abutments is approximately at right angles or perpendicular to the plane of the lower portion 30 of the sides to provide firm or solid contact with the frame member 14 in the event of a tilt. Also, the dimensioning is such that when the container or receptacle is fully open with the portions 30 generally horizontal, the upper surfaces 64 of the lower abutments will contact the length 14 of the base.

The use, operation and function of the invention are as follows:

Two side plates are provided which are supported by a base or frame. The side plates are outwardly bowed or convex or bent, as shown in the drawings, so that they abut adjacent their lower edges and come together again adjacent their upper edges. The upper portion at the top edge may be outwardly bent to form diverging lips to provide easy access for magazines. One, two or three or any number of suitable hinges may be provided to interconnect the lower edges to complete the container or receptacle.

One of the advantages of the present structure is that the weight of magazines in the container will bear downwardly on the pivot or abutting edges 28. Since the side plates 26 will be supported on the lower surfaces 62 of the upper abutments 58 which rest on the length 14 of the frame or bent wire, the weight will cause each of the plates to pivot about such length. Thus, the upper portion or lips will be biased toward each other at all times. Even when magazines are not present in the rack or receptacle, the weight of the parts themselves will cause the upper edges to come together because the pivot point between the length 14 and the upper abutments 58 is outside of the center of gravity of each side plate.

The ribbed or fluted structure of the side plates gives decided strength to the members. This is particularly true when a number of magazines of substantial weight are put into the receptacle. The ribs prevent the lower portions 30 of the side plates from flexing excessively. Additionally, the ribs insure that thinner and less expensive plastic may be used.

At the same time, the weight of the parts is such that the upper edges or bends 38 are not brought together with such force that a magazine cannot be pushed with ease down through the mouth or trough 40.

The base or frame which supports the plastic plates is reliable and simple. The end portions, formed as shown and described, perform the double function of end closures and handles. The downwardly bent portions at 16, 18 and 20 provide a four legged base or support.

Whereas the preferred form has been shown and described and several modifications have been suggested, it should be understood that suitable additional modifications, changes, substitutions and alterations may be made without departing from the invention's fundamental theme. It is therefore wished that the invention be unrestricted, except as by the appended claims.

I claim:

1. In a magazine rack or the like, a base, generally upright laterally opposed plates on the base biased toward each other and defining a receptacle between them for magazines, and outwardly turned lips at the top of the plate defining an entrance and exit for such magazines, the base being an open wire frame formed into four legs for the support of the receptacle and defining lateral guards across the ends of the plates to close the otherwise open ends of the receptacle.

2. The structure of claim 1 further characterized in that the lateral guards are bent outwardly to form handles.

3. In a magazine rack or the like, a base, generally upright laterally opposed plates on the base biased toward each other and defining a receptacle between them for magazines, and outwardly turned lips at the top of the plate defining an entrance and exit for such magazines, the plates being each bowed outwardly from the bottom edge toward the top, and further including a plurality of outwardly disposed projections on the lower portion of such outwardly bowed portion for engaging the base.

4. The structure of claim 3 further characterized in that the plates are disposed symmetrically opposite each other.

5. In a magazine rack or the like, a supporting frame, laterally opposed plates for and supported by the frame and defining a receptacle for magazines, the plates being hinged together along their bottom edge and convex above the bottom edge coming together adjacent their upper edge, the frame including longitudinal lengths engaging the convex sides of the plates and formed, in combination with the weight of the plates, to function as sliding pivots so that the upper edges of the plates will be biased together at all times, and a plurality of outwardly disposed downwardly facing projections on the lower portion of convex sides of the plates for engaging the base.
